ULTRAVIOLET LIGHT APPARATUS

Emil R. Capita, North Bergen, N. J.

Application September 9, 1944, Serial No. 553,442

7 Claims. (Cl. 315—248)

1

This invention relates to ultraviolet light generation and is herein disclosed in some detail as embodied in various devices employing an induced mercury vapor current which creates the desired arc-forming current for the radiations of ultraviolet light. The ultraviolet light is shown in one structure as generated within a hollow-walled container having one or more walls of quartz or of other material adapted to transmit ultraviolet light, with the result that the container delivers the light over a large area and thus a properly shaped container may efficiently utilize the light uniformly and effectively.

In another form, the hollow walls in which the mercury arc is created may deliver the ultraviolet outwardly, as from a cylinder. In this form, the device is shown with the exciting high-frequency coils laid against the inner surface of a hollow-walled cylinder so that the mercury arc forming within the walls generates ultraviolet light which is shown as radiating radially from a cylinder. It is likewise possible to generate the mercury arc in a hollow curved surface such as a hemisphere, with the exciting coil on the convex surface, so that the resulting ultraviolet light focuses, for example, on an object at the focal center of the curved surface. In the form shown, the hollow walls in which the mercury arcs form, may be filled with a small quantity of argon or other inert gas and may contain sufficient mercury to form the desired arc when vaporized. A current of proper frequency and amplitude in the high-frequency coils lying against one wall of the ultraviolet light generator induces an oscillating current in the gas column generating heat. This heat vaporizes part of the mercury which results in a mercury-vapor arc. The walls may extend beyond the ends of the exciting coil, thus providing a zone where mercury can condense and thus an apparatus may be built to provide a wide variety of mercury vapor pressures and consequently a wide range of arc striking potentials.

An arc in the hollow walls of a hollow cylinder, for example, enables a piece of meat to be kept sterile at almost any desired temperature by uniformly distributed ultraviolet rays, so that it may be safely kept at a temperature for the processes to go on within the meat that "tenderize" it by "hanging."

Other and further objects of the invention will be obvious upon an understanding of the illustrative embodiment about to be described or will be indicated in the appended claims and various advantages not referred to herein will occur to

one skilled in the art upon employment of the invention in practice.

A preferred embodiment of the invention has been chosen for purposes of illustration and description and is shown in the accompanying drawings, forming a part of the specification, wherein

Fig. 1 is a diagrammatic sectional side view of a ring-shaped mercury arc utilized as a meat tenderizer;

Fig. 2 is a similar view of a cylinder adapted to radiate ultraviolet light from the periphery;

Fig. 3 is a similar view of a cylinder having walls that project beyond the exciting coil to maintain a special mercury vapor pressure; and

Fig. 4 is a similar view of a curved surface adapted to focus ultraviolet light upon a small area.

In the form shown in Fig. 1, a cylinder 10 having a hollow wall 11 is shown as surrounded throughout its length by a coil 12, diagrammatically shown. The coil is adapted to carry a high-frequency current supplied by terminals 13 and 14, so that the current may excite an ionic discharge in the inert argon or other gas confined between the inner wall 15 and the outer wall 16, with the result that the annular chamber 11 formed by the hollow walls is heated.

The heat increases until the mercury 17 contained in the chamber 11 is partly or wholly vaporized. The vaporized mercury becomes the predominating conductance in the chamber 11 and an induced mercury arc forms in the chamber.

The arc thus formed delivers ultraviolet light radially inwardly upon, for example, a carcass 35 of meat 18 hanging in the cylinder 10, being suspended from a transverse non-conducting cross-piece 19 by a hook 20. The ultraviolet light is efficient and effective because the inner wall 15, made of quartz or some glass adapted to pass the ultraviolet light, transmits ultraviolet light uniformly about the carcass. Since the ultraviolet light impinges from all sides and effects sterilization, the meat may hang as long as is required for it to become tender without danger of spoilage, and, by properly regulating the conditions, the vitamin D content of the meat increased.

In the form shown in Fig. 1, the bottom of the cylinder is closed by a convex hollow-walled cover 21 against the outside of which lie concentric coils 22 which may be separately excited by terminals 23, 24. The cover 21 includes a separate chamber 25 carrying its own argon or other gas and its own charge of mercury. The inner wall 21a is preferably of some material

transparent to ultraviolet light like the wall 15.

In the form shown in Fig. 1, the top of the cylinder is also closed by a convex hollow-walled cover 26 against the outside of which lie concentric coils 27 excited by special terminals 23, 29 so that the hollow chamber 30 between its walls carrying its own charges of argon and mercury, may be properly heated to form its own mercury arc emitting the same ultra-violet rays to pass through the inner surface transparent to ultraviolet light.

The cover 26 may be lifted by a hoist 31 and may include openings 32 and 33 for circulating air, pre-filtered if desired, through the cylinder to absorb the heat radiated by the arcs in the chambers 11, 25, 30 into the closed interior of the cylinder 10.

The outer wall 16 and coil 12 may be surrounded by a protective cover or enclosure 7, preferably water-tight, so that the device may be scrubbed with water without damage.

In the alternative device shown in Fig. 2, ultraviolet rays are radiated outwardly through the outer wall 34 of a cylinder 35 which includes an inner wall 36 and a coil 37 lying inside the inner wall. The annular hollow chamber 38 contains argon or other suitable gas and mercury and the coil 37 is adapted, when excited by a suitable high-frequency current, to form a mercury arc within the chamber 38 and thereby radiate ultraviolet light through the outer wall 34 which is transparent to ultraviolet light.

The cylinder 35 of Fig. 2 is shown as provided with a bottom cover 39 and a top cover 40 with the leads 41 and 42 passing through the cover 40 and connected to the respective ends of the coil 37. The covers 39 and 40 are shown as provided with ventilating openings 43 to cool off the interior.

The alternative device shown in Fig. 3 illustrates how the ultraviolet ray emitting device with an inner wall 44 and an outer wall 45 may be so built as to attain maximum efficiency of the mercury arc which generates the light.

In the form shown in Fig. 3, the exciting coil 46 with terminals 47, 48 lies outside the outer wall 45 but covers only part of its length, leaving the lower end 49 of the annular chamber 50 between the walls bare of winding with the result that the chamber 50 is relatively cold at that end. Mercury, therefore, condenses at that end and thus controls mercury vapor pressure and the consequent striking potential of the mercury column in the presence of the argon or other gas. The cylinder formed by the walls 44, 45 is shown closed at the top by a convex cover or continuation 51 of the chamber 50 formed by continuations 52, 53 of the walls 44, 45. The convex continuation is shown as carrying coils 54 having a terminal 55 for use instead of the terminal 47, when the cylinder carries the continuation 51.

The invention also provides a device shown in Fig. 4 which focuses ultraviolet light at a point 56. In this form, the ultraviolet light is shown as proceeding from the curved surface 57, which may take the form of a segment of a hollow sphere. To attain this end, the face 57 is shown as the hollow wall of one side of a chamber 58 forming a segmental portion of a sphere, the other or outer wall being shown at 59. The chamber 58 contains mercury and argon or other gas, and, like the chambers of Figs. 1, 2 and 3, is excited by a high-frequency coil 60 to heat by ionic discharge and then produce an ultraviolet

light-yielding mercury arc when excited by its terminals 61, 62.

It will be seen that the present invention provides an effective and efficient means for curing meats, for maintaining a sterile atmosphere in a predetermined space for providing a uniform distribution of ultraviolet light about an object, and for similar purposes. The device is simple in construction, easy to operate and readily adapted for different purposes. The device may be cleaned without danger of impairing the electric insulation and is otherwise adapted to withstand any rough usage to which it may be subjected.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described in some detail certain embodiments of my invention, I claim:

1. An ultraviolet light apparatus comprising a chamber having at least two spaced coextensive walls and containing a charge of mercury and an inert gas therebetween, a wire for carrying a high frequency current adjacent one of the walls and having convolutions extending a substantial distance along a surface of said wall to energize the mercury in the chamber and maintain therein a mercury arc of shape corresponding to that of said chamber and radiating ultraviolet light, one of said walls having a concave surface defining an article-receiving compartment and for converging the emitted light into said article-receiving compartment.

2. An ultraviolet light apparatus for uniformly radiating converging ultraviolet light into a compartment adapted to receive objects to be treated by said light, comprising an enveloping chamber bounded by a first wall adjacent to said compartment and by a second wall coextensive with and spaced from said first wall, said walls being concave in relation to said compartment, a charge of mercury and an inert gas within said enveloping chamber, a wire for carrying a high frequency current having convolutions extending over the major portion of a surface of one of said walls to energize the mercury in the enveloping chamber and maintain therein a mercury arc producing an ultraviolet light radiating through said first wall to converge within the compartment.

3. An ultraviolet light apparatus comprising a first substantially hemispherical wall transparent to ultraviolet light, a second substantially hemispherical wall uniformly spaced from said first wall to form a substantially hemispherical chamber therebetween, a charge of mercury and inert gas in said chamber, a coil of wire adjacent one of said walls and adapted to carry a high frequency current to energize the mercury in the chamber and maintain therein a mercury arc producing ultraviolet light to radiate through said first wall.

4. The combination with a curved wall and a coil of wire adjacent it having convolutions thereof extending a substantial distance along said wall, of a second curved wall substantially coextensive with said first curved wall spaced opposite the first curved wall and transparent to ultraviolet light and forming with the first-mentioned curved wall an intermediate curved chamber, and mercury and argon gas within the intermediate chamber adapted to produce and

maintain an arc in said intermediate curved chamber by means of the current induced by a high-frequency current in said coil so as to deliver ultraviolet light through said oppositely spaced curved wall.

5. The combination with a cylindrical wall of a second cylindrical wall spaced from the first wall and forming therewith an intermediate tube-like space, a coil of wire lying adjacent and along a surface of one of said walls for carrying a high-frequency current to excite a conducting gas in the tubelike space intermediate said walls, said other wall being transparent to ultraviolet light and surrounding a compartment on its concave side, and mercury between said walls to generate ultraviolet light in said tubelike intermediate space when excited to form an arc and deliver converging ultraviolet light within the compartment.

6. The combination with a cylindrical wall of a second cylindrical wall spaced interiorly of and within the confines of the first wall and forming with said first wall a tubelike space, a coil of wire adjacent one of said walls and extending over a major portion of the area thereof adapted to carry a high-frequency current to excite a conducting gas in the tubelike space between said walls, said other wall being transparent to ultraviolet light and enclosing an article-receiving compartment at its concave side, and mercury and an inert gas in the tubelike space between said walls to generate ultraviolet light when excited to form an arc in said tube like space and deliver converging ultraviolet light within the article-receiving compartment.

7. Apparatus of the class described comprising the combination of coextensive substantially cylindrical double walls forming an intermediate tubelike space between said double walls and surrounding an article-receiving compartment, an innermost of said double walls being concave and transparent to ultraviolet light, a conducting coil extending over the majority of the area

of an outermost of said double walls for carrying a high-frequency current to excite a conducting gas in said intermediate tubelike space, coextensive substantially dome-shaped double walls forming an intermediate continuous dome-shaped space and closing one end of said article-receiving compartment, an innermost wall of said dome-shaped double walls being transparent to ultraviolet light, a conducting coil extending over the majority of the area of an outermost of said dome-shaped double walls for carrying a high-frequency current to excite a conducting gas in said intermediate dome-shaped space, and mercury and an inert gas in the intermediate spaces between the walls of each of said double walls to generate ultraviolet light and excite to arc in said intermediate spaces.
